(57) **CLAIM**

The ornamental design for a battery section of an electronic vaping device, as shown and described.

DESCRIPTION

FIG. 1 is a rear perspective view of the battery section of an electronic vaping device;

FIG. 2 is a rear view of the battery section of an electronic vaping device;

FIG. 3 is a front view of the battery section of an electronic vaping device;

FIG. 4 is a side view of the battery section of an electronic vaping device;

FIG. 5 is a top view of the battery section of an electronic vaping device;

FIG. 6 is a bottom view of the battery section of an electronic vaping device; and,

FIG. 7 is a front perspective view of the battery section of an electronic vaping device.

In the drawings, the claimed design is defined by the shaded surfaces; broken lines immediately adjacent shaded surface represent boundaries of the claim and form no part thereof; all other broken lines depict unclaimed environmental subject matter and form no part of the claim.
